United States Patent Office

Des. 198,408
Patented June 9, 1964

198,408

JUG

Thomas B. Craig, Midland, and Richard L. Platte, Ann Arbor, Mich., assignors to The Dow Chemical Company, Midland, Mich., a corporation of Delaware

Filed Dec. 30, 1963, Ser. No. 77,980

Term of patent 14 years

(Cl. D58—5)

Fig. 4

Fig. 3

Fig. 1

Fig. 2

FIGURE 1 is a front elevational view of a jug, showing our new design;

FIGURE 2 is a side elevational view thereof as seen looking toward the right-hand end of FIGURE 1;

FIGURE 3 is a side elevational view thereof as seen looking toward the left-hand end of FIGURE 1; and

FIGURE 4 is a top plan view thereof.

We claim:

The ornamental design for a jug, as shown.
